US0D1102451S

(12) **United States Design Patent** (10) **Patent No.:** **US D1,102,451 S**
Fountain et al. (45) **Date of Patent:** **** Nov. 18, 2025**

(54) **DISPLAY SCREEN OR PORTION THEREOF WITH A GRAPHICAL USER INTERFACE**

(71) Applicant: **Recover Strategies Corp.**, Miramar, FL (US)

(72) Inventors: **Cecile Fountain**, Miramar, FL (US); **Michelle Chitjian**, Commack, NY (US)

(73) Assignee: **Recover Strategies Corp.**, Miramar, FL (US)

(**) Term: **15 Years**

(21) Appl. No.: **29/940,840**

(22) Filed: **May 6, 2024**

(51) LOC (15) Cl. **14-04**

(52) U.S. Cl.

USPC **D14/485**

(57) **CLAIM**

The ornamental design for a display screen or portion thereof with a graphical user interface, as shown and described.

DESCRIPTION

The sole FIGURE is a front view of a display screen or portion thereof with a graphical user interface, showing our new design.

The outermost broken lines show a display screen or portion thereof and form no part of the claimed design. The remaining broken lines showing portions of the graphical user interface form no part of the claimed design.

1 Claim, 1 Drawing Sheet
